UNITED STATES PATENT OFFICE.

WILLIAM A. JAMESON, OF NIAGARA FALLS, NEW YORK.

DESIGN FOR A SPOON OR SIMILAR ARTICLE.

42,840.

Specification for Design.

Patented July 30, 1912.

Application filed November 22, 1911. Serial No. 661,868. Term of patent 7 years.

To all whom it may concern:

Be it known that I, WILLIAM A. JAMESON, a citizen of the United States, residing at Niagara Falls, in the county of Niagara and State of New York, have invented a new, original, and ornamental Design for a Spoon or Similar Article, of which the following is a specification, reference being had to the accompanying drawing, forming a part thereof.

The nature of my design is illustrated in the accompanying drawing to which reference is made, and in which—

Figure 1 is an obverse view of a spoon or similar article, and Fig. 2 is a reverse view thereof.

My design is applied to a handle 1 of a spoon or similar article. The handle is outlined by a raised or embossed marginal portion 2 on both sides, and near the end on the obverse side is an embossed spray of flowers and head framed thereby. A smaller group of flowers is preferably embossed near the connection of the bowl and handle.

I claim:

The ornamental design for a spoon or similar article as shown and described.

WILLIAM A. JAMESON.
